United States Patent Office.

FRANK H. McGEORGE, OF CORNING, NEW YORK.

Letters Patent No. 97,947, dated December 14, 1869.

IMPROVEMENT IN GATES.

The Schedule referred to in these Letters Patent and making part of the same.

To all whom it may concern:

Be it known that I, FRANK H. McGEORGE, of Corning, in the county of Steuben, and State of New York, have invented a new and useful Improvement in Gates; and I do hereby declare that the following is a full and exact description of the same, reference being had to the accompanying drawings, and to the letters of reference marked thereon.

This invention relates to that class of gates which is operated by means of cords and rings or handles, for the purpose of enabling persons on horseback or in carriages to enter without dismounting to open the gate; and

It consists—

First, in the combination of stationary pulleys with a slotted wheel attached to the top of the main gate-post, which moves horizontally upon a pin in the plate of the post-cap.

Second, with a catch of peculiar construction, by means of which the gate is securely held when open.

Third, in the peculiar construction and arrangement of parts, whereby the operating-mechanism is compactly located in the cap of the bearing-post, and securely protected from the weather.

In the drawings—

Figure 1 represents a side elevation of the gate when opened.

Figure 2 represents a plan view, with the gate closed.

Figures 3, 4, and 5 represent views of parts detached.

To enable others skilled in the art to make and use my invention, I will now proceed to describe fully its construction and operation.

A and A' represent foundation-beams, which are laid down and secured in any proper manner.

B B' represent the posts, between which the gate swings, and

B² B²', the pulley-posts, which support the cords and rings, as shown.

The peculiar construction of the posts B¹ B² B²' is not essential, as no part of my invention relates to them.

The post B, however, is provided with a hollow cap, B², within which the main part of my operating-mechanism is located.

The cover of this cap should be made removable, in order that the mechanism can be easily reached when desired.

b represents the plate of the cap, which is provided with the slots b' and catches b'', as shown in fig. 4.

C represents the gate, and
c, the gate-head.

The lower part of this head is provided with a forked arm, which bears against pins or rods, either within the post, or without, as may be preferred, in the usual well-known manner.

The upper part of the head is provided with a grooved wheel, c', which is attached to it near its circumference, (i. e., the wheel,) as shown.

This wheel is secured to the plate of the post-cap by means of a pin, which projects upward from the plate, as shown in fig. 4, and fits in a slotted socket in the wheel.

D D represent pulleys, arranged at equal distances from the wheel c', about which pass the cords e e.

These cords are attached, at their outer ends, to the hand-rings E E, which should be heavy enough to keep the cords tight at all times. From this point, the cords pass over the pulleys, f f, on the pulley-posts, through the flange of the bearing-post cap, about the pulleys D, around the wheel c', to which latter they are securely attached, at the point x.

The operation of my improved gate is as follows:

When it is desired to open the gate from either side, the person approaching pulls the ring upon the pulley-post. By this means, the wheel c' is first pulled backward upon its pin, and, as the lower part of the gate-post c is stationary, it therefore follows that the front of the gate is tipped up. By this means, the latch is cleared for the catch, and the gate is free to swing. The continued strain upon the rope now revolves the wheel c', and the gate is necessarily opened thereby.

As the top of the main gate-post c moves into the slot, b¹, in the plate, it passes the catch b'', and is thus securely held open.

When the gate has been passed through, a slight pull at the opposite ring will draw the gate-post back from the catch, and set it free, when it will close at once by its own weight.

The bearing-post should be arranged with one of its corners in line with the gate, in order that the latter may be free to swing in either direction without obstruction.

The plate of the cap may be constructed of a single piece of metal, and the cover also of a separate piece.

If desired, the pulley-post may be also similarly covered, and the whole may be connected by a pipe or cover of any suitable form.

The principal operating-parts may be placed in caps, which may be attached to any post by an ordinary mechanic.

The device herein described is extremely simple in all its parts, and yet exceedingly effective in operation.

Having thus fully described my invention, What I claim as new, and desire to secure by Letters Patent, is—

1. The combination of pulleys D D with the slotted wheel c', when arranged as described, and used in connection with a gate and bearing-post, for the purpose set forth.
2. The slotted plate b, with its catch b², as described, for the purpose set forth.

3. The hollow cap B¹, in combination with the pulleys and wheel, when provided with a cover, as and for the purpose set forth.

This specification signed and witnessed, this 18th day of October, 1869.

F. H. McGEORGE.
